LOCKED WALL PANEL JOINT WITH FASTENER
Resta S. Gregoire, Dillsburg, Pa., assignor to Gregoire
Engineering and Development Company
Filed Aug. 23, 1962, Ser. No. 218,990
3 Claims. (Cl. 52—509)

This is a continuation-in-part of application Serial No. 194,339, filed May 14, 1962.

This invention relates to self interlocking sheet panel strips for wall construction and hidden mounting means therefor.

The object of the present invention is to provide lengthwise rigidity to the panel strips not only by internally protruding ridges of triangular section on the inner face of said strips, but also by either curved or angular corrugations of various suitable forms.

A further object is to devise hidden fastening means for these panels when mounting the successive panels on suitably spaced wall supports, thus providing the necessary rigid backing for the panel strips crosswise thereof.

A further object is to devise a form of panel strip providing maximum heat reflection outwardly and minimum heat radiation inwardly of the panel strips, so as to inherently provide maximum heat insulation for walls exposed to the sun in hot climates.

Other and more specific objects will become apparent in the following detailed description of several modifications of panel strips of sheet material corrugated or ridged lengthwise to provide longitudinal rigidity, and means for fastening them on crosswise extending supports to provide them with lateral rigidity, as illustrated in the accompanying drawings, wherein:

FIG. 1 is an end view in perspective of a panel strip formed substantially as disclosed in the copending application, above referred to,

FIG. 2 is a similar view of a modified form of angularly corrugated panel strip,

FIG. 3 shows a further modification of angular corrugation,

FIG. 4 is a modification showing a curvular corrugation,

FIG. 5 shows a modification combining substantially triangular grooves flanked by cylindrically curved depressions facing the outer face of the panel strip,

FIG. 6 is an end view of a joint between two panel strips showing a fastener clip nailed to a wooden support beam on which the panel strips are mounted,

FIG. 7 is an enlarged perspective view of this fastener clip,

FIG. 8 shows a side view of a modified fastening means, and

FIG. 8A shows a top view thereof.

The panels disclosed herein include the edge conformations similar to those shown in the copending application, to form the same type of simple self-locking and sealing joint between successive panel strips. Several new modifications of the panel configuration between these edges, however, are here disclosed, which provide the longitudinal rigidity to the panel strips by corrugations of various forms.

As before disclosed, the opposite edges of a panel strip are provided with cooperating edge formations to form a joint between successive panel strips in a wall. One of the edge formations is a substantially triangular groove 2 extending inwardly from the inner face of the panel strip, such as 4 in FIG. 1, 6 in FIG. 2, 8 in FIG. 3, 10 in FIG. 4, or 12 in FIG. 5, the triangular groove having one side 14 extending inwardly with reference to the inner face of the panel strip and somewhat outwardly of the panel strip at an obtuse angle, the base of the triangular groove

2

extending from the outer end of said one side, around a lobe 16 outwardly of said base, which is substantially parallel to the panel strip, then around another similar lobe 18 at the other end of said base to the outer end of the other side 20 of the triangular groove which has its upper or front end joining the outer face of the panel strip adjacent to the edge of the outer face of the panel strip but spaced therefrom normally the thickness of the panel sheet to permit passage of the other of the edge formations 22 of an adjoining panel strip. This other edge formation is an angular tongue or extension of the other edge of the adjoining panel strip bent rearwardly at an obtuse angle to the panel substantially complementary to the acute angle at which the side 20 of the triangular groove joins the face of its panel, said extension 22 being adapted for insertion into said triangular groove and interlocking therewith, so that as the adjoining panel strips are brought into alignment, a leverage pressure at two points of contact between the edge formations at 26 and 28 provides a double seal in the joint between the panel strips.

The inner sides of the outer lobe 16 are depressed close to the base of the triangle in the present instance, to provide a ridge and groove, over which the clip fastener 30 may be nailed by nail 32 to a wooden support beam 34 in mounting each panel strip in place before installing the next one, which hides the fasteners on the preceding panel strip.

The walls thus formed may be used without any lining for insulation or for decorative purposes, or suitable linings may be used between or over the ridges as may be desired, with possible provision for ventilation through the passages formed between the ridges or corrugations, as described in pending application Serial No. 200,682 filed June 7, 1962, entitled Panel Building Structure and Assembly.

A modified nail structure 24 having a lug 36 extending from its head may be used for fastening more firmly over the ridge of the lobe 16 in place of the clip fastener 30 and nail 32.

The form of panel strips shown in FIG. 1 provide a substantially continuous plain surface interrupted only by very narrow spacings at the open apexes of the triangular ridges and joints extending inwardly from the inner face of the panel strip, to permit thermal expansion of the adjacent panels without buckling, as already described in the pending applications.

The forms of panels illustrated in FIGS. 2 to 5 are modifications which present more open grooves in the face of the panels, thus using somewhat less material per square foot of wall without sacrificing longitudinal rigidity for the same thickness of wall. At the same time, the different forms of grooves provide not only a choice of appearance, but also a selectivity of size and spacing of functional grooves, providing more or less concentration and direction in narrow grooves such as 50 in FIG. 3 or wide grooves such as 52 in FIG. 2, and 54 in FIG. 4, for drainage flow over inclined walls.

The form shown in FIG. 5 furthermore provides arcuately curved reflecting surfaces 56, not only to reduce absorption of heat into the wall but also to reduce radiation inwardly of the wall of the heat that has been absorbed, by radiating it fanwise, thus reducing its concentration.

Many other obvious modifications in the form and details of the several parts may be made without departing from the spirit and scope of the present invention as defined in the appended claims.

What is claimed is:

1. A locked wall sheet panel joint and fastener com-

bination for mounting panel strips in successive joined relation onto a wall support, comprising

a pair of wall sheet panel strips each having a terminal elongated edge formation,

one of said edge formations being seated within the other of said formations and locking the strips together with their adjoining outer faces substantially coplanar,

the other of said edge formations being a substantially triangular groove extending inwardly from said outer faces, the inside and outside side walls of said triangular groove diverging from an open apex in the plane of said outer faces towards the base of said triangle, and extending further apart near both ends of the base to define hollow lobes adjoined thereto, said base being substantially parallel to said outer faces and being anchored to said wall support, one of said lobes defining an inwardly directed shoulder within said groove and part of the inside side wall connecting the base to its respective strip, the other of said lobes defining an exterior outwardly directed shoulder on the outside side wall which has a free terminal end at said open apex,

said one of said edge formations being an angular tongue extending inwardly from the outer face of its respective strip through said open apex and having a reversely turned lip at the end of said tongue resiliently pressing against said inwardly directed shoulder on the inside side wall of said triangular edge formation, forming a line-contact pressure seal in said joint and locking said strips together, the free end of said outside side wall of the triangle being biased against the inner face of the base of said tongue, and

fastener means fixed to said wall support having head portions extending over the outwardly directed

shoulder of said other lobe to anchor said joint against said wall support.

2. A joint and fastener combination as defined in claim 1, the outside side wall of the triangle having an outwardly turned ledge at its free terminal end with its outer edge biased against the inner face of the base of said tongue to provide a second line-contact pressure seal in said joint.

3. A joint and fastener combination as defined in claim 1,

said fastener means being a nail with an extension from its head and driven into said wall support next to said joint so that said head extension clamps over said outwardly directed shoulder to anchor said joint to said wall support without puncturing said joint.
